Attorney.

UNITED STATES PATENT OFFICE.

HORACE E. SMYTHE, OF PITTSBURGH, PENNSYLVANIA, ASSIGNEE TO THE S. R. SMYTHE COMPANY, OF PITTSBURGH, PENNSYLVANIA, A CORPORATION OF WEST VIRGINIA.

PREHEATING-FURNACE.

1,322,208.

Specification of Letters Patent. Patented Nov. 18, 1919.

Application filed July 8, 1919. Serial No. 308,386.

To all whom it may concern:

Be it known that I, HORACE E. SMYTHE, a citizen of the United States, residing at Pittsburgh, in the county of Allegheny and State of Pennsylvania, have invented new and useful Improvements in Preheating-Furnaces, of which the following is a specification.

My invention relates to preheating furnaces, and more particularly to improvements in the preheating apparatus shown in my Patent No. 1,305,176, granted May 27, 1919.

The object of the present invention is to provide means for spacing and bracing the wall of the regenerating flues; to increase the area of the heat-absorbing surface; and to impede the flow of the gases and thereby increase the time for the absorption of their heat by the flues. Other objects appear hereinafter.

On the accompanying drawings, Figure 1 is a longitudinal vertical section of a furnace containing my invention, the section being taken on the line I—I of Fig. 3; Fig. 2, a horizontal section on the line II—II of Fig. 1; Fig. 3, a vertical cross-section on the line III—III of Fig. 1; and Fig. 4, a section of a portion of two adjacent walls 80 and a few of the bracing and tying bricks or bars.

On the drawings, 1 designates a furnace chamber lying above two preheating chambers 2 and 3, separated by the wall 4 extending transversely of the furnace chamber. 5 represents the stack. 6 and 7 are two chambers on opposite sides of the stack, the former connected by the flue 8 to the opening 9 leading into the inner end of the chamber 2, and the latter connected by the flue 10 to the opening 11 into the inner end of the chamber 3.

Through the usual reversing valves, not shown, the chamber 6 at one time supplies air or gas to the preheating chamber 2 by way of the passage 8 and the opening 9 while the chamber 7 receives the waste gases from the chamber 3 by way of the opening 11 and passage 10 and delivers them to the stack 5. Upon reversal of the said valves the functions of the chamber 6, the passage 8, and the opening 9 on the one hand, and of the chamber 7, the passage 10, and the opening 11 on the other hand are reversed 55 in the well known manner.

Beyond the bridge walls 12 and 13 at the opposite ends of the furnace chamber 1 are the vertical flues 14 and 15, the former leading to the outer end of the chamber 2 and the latter to the outer end of the chamber 3. 60 Beneath the flues 14 and 15 are the slag-pockets 16 separated from the remainder of the chambers 2 and 3 by the vertical walls 17 having the ports 18 at the top. The slag pockets 17 have the doors 19 which may be removed to admit tools for the purpose of cleaning and repairing. 65

The structure within the chambers 2 and 3 is alike. Only that within the chamber 2 will be described. The portion of the chamber 2 between the walls 4 and 7 is provided with several vertical baffles or walls 20 to 25, which except the baffles 20 and 25 start alternately from the opposite sides of the chamber and stop short of the opposite side, 70 forming the flues 26 to 31 at the ends of the baffles. The baffles 20 and 25 do not reach either side of the furnace, whereby the double parallel flues 32 and 33 are provided at the outer ends of the chamber 2, and similar flues 37 and 38 are provided at the inner end thereof. Single flues 34 to 36 are provided between the consecutive baffles 21 to 24. All the baffles extend from the floor of the chamber to the roof, there being small 75 by-pass openings provided at the top and bottom.

The lateral walls of the flues 32 to 38 are provided with horizontal bricks 39 having their ends in openings (Fig. 4) in the said walls. These bricks serve as girders for bracing and spacing the walls and tying them together. They also break up and retard the flow of the gases so as to give increased time for heating the heat-absorbing 95 surfaces in the chamber, and they increase the area of the said heat-absorbing surfaces.

Supposing the chamber 6 to be connected to a supply of air and the chamber 7 to the stack 5, the air will flow from the chamber 6 through the passage 8, the opening 9, the flue 31, the flues 37 and 38 in parallel, the flues 30, 36, 29, 35, 28, and 34 in series, the flues 27, 32, 33, and 26, the port 18, and the flues 16 and 14 to the furnace chamber 1 100 where the air meets with a supply of gas which may be preheated in a similar manner, if preferred. From the chamber 1 the hot waste gases pass over the bridge-wall 13 and down the flue 15 to the right-hand pocket 16 105 110

- where they drop slag and other heavy foreign matter. From the said pocket 16 the gases pass through the chamber 3 after entering by the port 18. The course of the 5 gases through this chamber is the reverse of that just described for the air through the chamber 2. The gases leave the chamber 3 through the opening 11 and reach the stack 5 through the passage 10 and the chamber 7. 10 The gases passing through the chamber 3 highly heat all the surfaces along which they pass, the girders 39 absorbing a large amount of heat and slowing up the flow of the gases. 15 If now the reversing valves are moved so as to open the chamber 6 to the stack 5 and the chamber 7 to the air supply, the air and waste gases will take the opposite course to those taken before the valves were reversed. 20 The air will be highly heated in passing through the chamber 3 and the waste gases from the furnace chamber will highly heat the chamber 2. When the valves are again reversed, the air will be heated by the chamber 2 and the waste gases will heat the chamber 3. The valves are alternately thrown in opposite directions at such intervals of time as will best heat the air and the preheating chambers. 25 Numerous openings 40 are provided in the sides of the chambers 2 and 3 whereby nozzles of hose conveying air, water or other cleaning medium may be applied to the interior walls and the braces 39. These open-

ings will ordinarily be closed during the 35 normal use of the furnace.

I have not shown any apparatus for pre-heating fuel-gas. This may be accomplished by providing duplicate preheating chambers, reversing valves and gas passages such 40 as I have described for preheating air. 40' indicates openings for the entrance of fuel gas.

I claim:

1. In a preheating structure for air, gas, 45 or the like, a chamber having an inlet and an outlet, and between the same a series of vertical baffles arising alternately from the sides of the chamber and stopping short of the opposite side thereof and also extending 50 from the floor to the roof thereof, and braces connecting adjacent baffles whereby the baffles are kept in place, and the area of the heating surfaces of the chamber increased.
2. In a preheating structure for air, gas, 55 or the like, a chamber having an inlet and an outlet, and between the same a series of vertical baffles arising alternately from the sides of the chamber and stopping short of the opposite side thereof and also extending 60 from the floor to the roof thereof, and braces connecting adjacent baffles whereby the baffles are kept in place, and the area of the heating surfaces of the chamber increased.

Signed at Pittsburgh, Pa., this 23rd day 65 of June, 1919.

HORACE E. SMYTHE.
